CLOCK

Robert O. Fletcher, Ashland, Mass., assignor to General
Electric Company, a corporation of New York

Application September 30, 1954, Serial No. 32,495

Term of patent 7 years

(Cl. D42—7)

The figure is a front perspective view of a clock embodying my new design. The opposite side of the clock is the same in appearance as that shown.

I claim:

The ornamental design for a clock as shown and described.
